TRANSFERRER ARM FOR WEFT
REPLENISHING LOOMS

Carl P. Bergstrom, Millbury, Mass., assignor to
Crompton & Knowles Loom Works, Worcester,
Mass., a corporation of Massachusetts

Application June 10, 1949, Serial No. 98,244

7 Claims. (Cl. 139—244)

1

This invention relates to improvements in transerrer arms for weft replenishing looms and it is the general object of the invention to provide a transerrer arm which is readily adaptable for use with bobbins the wefts of which are of different diameters.

Bobbin changing looms ordinarily operate with reserve bobbins which are moved one at a time into a depleted shuttle by a transerrer arm. Under one condition of weaving a reserve bobbin may have a relatively small yarn diameter, but under another condition the yarn may have a larger diameter. As heretofore made transerrer arms have been able to meet only one particular set of conditions and have not ordinarily been adaptable for use with a variety of yarn diameters. The transerrer arm usually has a heel which engages the butt of the bobbin and also a part integral with the heel which engages the yarn so that the bobbin being transferred can be acted on at two points along its length.

It is an important object of the present invention to provide a transerrer arm having preferably a permanent yarn engaging part and a replaceable heel for engagement with the bobbin butt. If the yarn diameter is large relatively to the bobbin butt the heel will be relatively thick so that it can engage the butt of the bobbin at about the same time that the yarn engaging part of the transerrer arm strikes the wound package of yarn on the bobbin. If, on the other hand, the yarn diameter is small the heel will then be thin so that the bobbin engaging parts of the transerrer arm can strike the bobbin at substantially the same time during the transferring operation.

It is a further object of the invention to provide a transerrer arm so constructed that it can have one or another of two or more different heels secured thereto by readily detachable means.

With these and other objects in view, which will appear as the description proceeds, the invention resides in the combination and arrangement of parts hereinafter described and set forth.

In the accompanying drawings, wherein two forms of the invention are set forth,

Fig. 1 is a side elevation of part of a weft replenishing loom having the preferred form of the invention applied thereto, the lay, shuttle, and shuttle box being shown in cross section,

Fig. 2 is a front elevation looking in the direction of arrow 2, Fig. 1, showing the preferred form of the invention in use with a bobbin the butt and yarn diameters of which are substantially the same,

2

Fig. 3 is an enlarged vertical section on line 3—3, Fig. 2,

Fig. 4 is a section on line 4—4, Fig. 3,

Fig. 5 is a view similar to Fig. 2, but shows a bobbin having a relatively large butt and a smaller yarn diameter,

Fig. 6 is a view similar to Fig. 2, but shows the transerrer arm adapted for use with a bobbin the yarn diameter of which is larger than the butt diameter,

Fig. 7 is a view similar to Fig. 2, but showing the modified form of the invention adapted for use with a bobbin the butt diameter of which is larger than the yarn diameter,

Fig. 8 is an enlarged vertical section on line 8—8, Fig. 7, and

Fig. 9 is a section on line 9—9, Fig. 8.

Referring particularly to Fig. 1, the loom frame 10 has mounted thereon a support 11 for a magazine M which in the present instance is of the rocking type mounted on a pivot stud 12 carried by the support 11. The magazine has front and back stacks 13 and 14 of reserve bobbins which move by gravity to positions from which they can be transferred into one or the other of the two shuttles with which the loom operates, one of the shuttles being indicated at S. The latter at the time of weft replenishment will be in a shuttle box 15 on the lay 16, and the latter has a bunter 17 to engage a latch 18 on transerrer arm 19. The latter is pivoted on a stud 20 carried by the support 11 and is normally in the raised idle position indicated in Fig. 1 with the transerrer latch 18 in down position. By means of well-known mechanism not shown herein the latch 18 is lifted into alignment with the bunter 17 for engagement with the latter when a weft replenishing operation occurs. At this time forward motion of the lay, that is, motion to the left as viewed in Fig. 1, will cause the bunter to rock the transerrer arm 19 around the stud 20 to move a reserve bobbin from the magazine into the shuttle.

A latch holder 21 is pivoted at 22 to the transerrer arm 19 and is provided with an adjusting screw 23 engaging the forward end of latch 18 to determine the relative position of the latch with respect to the holder and transerrer arm. A bolt 24 secures the latch in its adjusted position to the holder. By varying the position of the latch the amount of motion of the transerrer arm can be changed, the motion being increased if the latch is adjusted rearwardly toward bunter 17, and reduced if the latch is adjusted forwardly 55 away from the bunter.

The transerrer arm, as shown more particularly in Fig. 2, has a heel supporting part 25 and a yarn engaging part 26 joined by a web 27. The web and the two parts 25 and 26 are integral and may be secured in any approved manner to the transerrer arm 19 and ordinarily form a part of the latter.

The bobbins in the magazine will ordinarily have a butt, a tip, and a wound mass of weft thereon between the butt and the tip. The bobbin shown in Fig. 2, designated at B1, has a butt 28 provided with the usual metallic rings 29. The yarn will be engaged by the part 26 of the transerrer arm, whereas the butt of the bobbin will be under the part 25.

The matter thus far described is of common construction and may operate in the usual manner.

The present invention relates to means for adapting the transerrer arm for use with a variety of conditions in which the weft or yarn package may be of different diameters. As shown in Fig. 2 the condition exists wherein the butt and yarn Y1 are of the same diameter so that the part of the transerrer arm which engages the butt should be at the same level as the bottom of part 26 of the transerrer arm. This result is accomplished in the preferred form of the invention by having the transerrer arm equipped with an angle shaped heel 30 having an upright shank 31 held to the transerrer arm by screws 32 extending into tapped holes 33 in the transerrer arm. The heel 30 has a horizontal shoe or foot 34 which is the part of the heel which has direct engagement with the metallic rings 29. The top of the foot has a surface 35, preferably flat, which fits closely against a similar surface 36 on the bottom of transerrer arm part 25. The under surface 37 of the foot is concave to fit rings 29.

In the condition shown in Fig. 2 the foot 34 will be of such a thickness that the concave surface 37 will engage the rings 29 at the same time that the bottom of part 26 of the transerrer arm engages the yarn Y1. If it be desired to use the transerrer arm with a bobbin B2 the yarn diameter Y2 of which is less than the diameter of rings 29 the conditions will then be as set forth in Fig. 5. Under these conditions a different heel 40 will be employed having a shank 41 similar to shank 31, but having a foot 42 which will be thinner than the foot 34 but otherwise similar to the latter to cooperate with the rings 29. The heel 40, having its under surface relatively high with respect to the yarn engaging part 26, will not engage the rings 29 until the yarn part engages the yarn Y2.

If, on the other hand, a bobbin B3 as indicated in Fig. 6 has a yarn diameter Y3 larger than the rings 29, a still different heel 45 will be utilized, this heel having a shank 46 similar to shank 31 and having a foot 47 which will be relatively thick so that its under surface can strike the rings 29 at the same time that the transerrer part 26 strikes the yarn Y3. The previously described screw 23 can be adjusted in accordance with the thickness of the foot of the particular heel being used.

It will thus be seen that the same transerrer arm is adaptable for use with a variety of forms of bobbins merely by being equipped with the correct heel for any given condition of yarn diameter. The screws 32 permit ready replacement of one form of heel with another.

In the modified form of the invention the transerrer arm 50 will be very similar to the trans-

errer arm 19 except that the lower end of the butt part 51 thereof will be adapted for holding a different type of heel. In describing the modified form only one condition of yarn diameter will be set forth, namely, that in which the diameter of yarn Y4 is less than that of rings 29, see Fig. 7. A heel 52 having a relatively thin foot 53 will be used under this condition. The foot is formed with a concave under surface 54 for engagement with the rings 29. A lug or shank 55 extends upwardly from the heel into a hole 56 drilled into the transerrer arm 50. A tapered pin 57 is driven through the lower part of the transerrer arm and the shank 55 and secures the heel 52 to the transerrer arm in position for correct engagement with the bobbin butt. The top surface 58 of foot 53 will be drawn up tightly against the bottom surface 59 of the transerrer arm part 51 by pin 57.

The modified form of heel lends itself to use under the same variety of conditions as those already described in connection with the preferred form of the invention. The foot of the modified heel can be of a thickness to suit the transerrer arm for use with any diameter of yarn. It is not thought necessary to illustrate other conditions in connection with the modified form, since the variations in thickness of the foot will correspond to conditions already described in connection with the preferred form of heel.

From the foregoing it will be seen that the transerrer arm has a yarn engaging part 26 and is so constructed that it can have secured thereto any one of several bobbin butt engaging heels 30 the feet of which are of different thicknesses to accommodate varying conditions of yarn diameter. The bottoms of the two parts 25 and 26 of the transerrer arm are at such a difference of level that they cannot engage the weft and butt of bobbins usually encountered in weaving, but by selecting the correct heel the difference in level between it and part 26 can be made the same as the difference in the radii of the butt and weft of the bobbin being transferred, and as a result both parts of the transerrer arm will strike the bobbin at substantially the same time during a bobbin transferring operation. In the preferred form of the invention the transerrer arm is made to receive the vertical shank of any one of several angle shaped heels, whereas in the modified form the transerrer arm has a hole 56 to receive the lugs or shanks 55. In the preferred form the screws 32 permit ready replacement of one heel by another, and in the modified form the replacement is effected by removal of the tapered pin 57.

Having thus described the invention it will be seen that changes and modifications of the foregoing specific disclosure may be made without departing from the spirit and scope of the invention.

What is claimed as new is:

1. In a transerrer arm for a weft replenishing loom operating with a reserve bobbin having a butt and a wound mass of weft, a part on the transerrer arm for engagement with the wound mass of weft a second part on the transerrer arm corresponding to the butt of the bobbin, a heel on said second part having a foot for engagement with the bobbin butt and having also a shank extending away from said foot, and removable means normally securing the shank to said second part of the transerrer arm to hold said foot in bobbin butt engaging position on the transerrer arm, the foot being of such thick-

ness that the first named part of the transferrer arm and said foot engage the yarn and butt, respectively, at substantially the same time during a bobbin transferring operation of the transferrer arm.

2. In a transferrer arm for a weft replenishing loom operating with a reserve bobbin having a butt and a wound mass of weft, a part on the transferrer arm for engagement with the wound mass of weft, a second part on the transferrer arm corresponding to the butt of the bobbin, a heel on said second part having a foot for engagement with the bobbin butt and having also a shank extending away from one end of said foot and removable means securing said shank to said second part to hold said foot in position to engage the bobbin butt, the foot being of such thickness that the first named part on the transferrer arm and said foot engage the yarn and butt, respectively, at substantially the same time during a bobbin transferring operation of the transferrer arm.

3. In a transferrer arm for a weft replenishing loom operating with a reserve bobbin having a butt and a wound mass of weft, a part on the transferrer arm for engagement with the wound mass of weft, a second part on the transferrer arm corresponding to the butt of the bobbin, said second part having a screw threaded hole therein, a heel on said second part having a foot for engagement with the bobbin butt and having also a shank extending from said foot along said second part, and a screw securing said shank to said second part of the transferrer arm fitting into said screw threaded hole and holding the heel to the transferrer arm with said foot in position to engage the bobbin butt during a bobbin transferring operation of the transferrer arm.

4. In a transferrer arm for a weft replenishing loom operating with a reserve bobbin having a butt and a wound mass of weft, a part on the transferrer arm for engagement with the wound mass of weft, a second part on the transferrer arm corresponding to the butt of the bobbin, said second part having a hole therein, a heel on said second part having a foot below the latter for engagement with the bobbin butt and having also a shank extending upwardly from said foot into the hole in said second part of the transferrer arm, and removable means passing through said second part of the transferrer arm and said shank securing the heel to the transferrer arm with said foot in position to engage the butt of a bobbin during a bobbin transferring operation.

5. In a transferrer arm for a weft replenishing loom operating with a reserve bobbin having a butt and a wound mass of weft, a part integral with the transferrer arm for engagement with the wound mass of weft, a second part on the transferrer arm corresponding to the butt of the bobbin, said second part of the transferrer arm having a hole extending upwardly

therein from the bottom thereof, a heel on said second part having a foot under the latter and formed with a shank extending into said hole, and a taper pin driven into said second part of the transferrer arm and through said shank holding the heel on the transferrer arm with said foot in position to engage the butt of a bobbin being transferred during a transferring operation of the transferrer arm.

6. In a transferrer arm for a weft replenishing loom operating with a reserve bobbin having a butt of a given radius and a wound mass of weft of a different radius, a part on the transferrer arm for engagement with the wound mass of weft, a second part on the transferrer arm corresponding to the butt of the bobbin, the difference in level between the bottoms of said two parts of the transferrer arm being different from the difference in the radii of the butt and wound mass of weft, a heel secured to said second part of the transferrer arm having a foot under said second part, and removable means holding said heel to said second part, said foot being of such thickness that the difference in level between the first named part of the transferrer arm and the bottom surface of the foot is equal substantially to the difference between the radius of the butt and the radius of said wound mass of weft of said bobbin.

7. In a transferrer arm for a weft replenishing loom capable of operating with bobbins the butt diameters of which vary with respect to the diameters of the weft mass on the bobbins, the transferrer arm to operate with any one of a plurality of different bobbin butt engaging heels having similar shanks and each heel having a foot, the feet of the different heels being of different thicknesses, a part on the transferrer arm for engagement with the wound mass of weft, a second part on the transferrer arm corresponding to the butt of the bobbin being formed to fit the shank of any of said plurality of heels, and removable means holding the shank of any selected heel to said second part of the transferrer arm with the corresponding foot in position to engage the butt of the bobbin being transferred, the foot of the selected heel and the first named part of the transferrer arm being effective during a bobbin transferring operation to engage the butt and mass of weft, respectively, of the bobbin being transferred at substantially the same time.
